J. P. HARRIMAN.

ORNAMENTATION OF KNIT FABRICS.

No. 18,363

Patented June 5, 1888.

UNITED STATES PATENT OFFICE.

JEREMIAH P. HARRIMAN, OF WOONSOCKET, RHODE ISLAND.

DESIGN FOR THE ORNAMENTATION OF KNIT FABRICS.

SPECIFICATION forming part of Design No. 18,363, dated June 5, 1888.

Application filed March 10, 1888. Serial No. 266,884. Term of patent 14 years.

To all whom it may concern:

Be it known that I, JEREMIAH P. HARRIMAN, a citizen of the United States, and a resident of Woonsocket, county of Providence, and 5 State of Rhode Island, have invented and produced a new and original Design for Surface Ornamentation of Knitted Fabrics, of which the following is a full, clear, and exact description, reference being had to the accompanying 10 photographic illustration, forming a part hereof, in which is represented a portion of a fabric with my invention applied thereto.

My design is intended for application generally to all forms of knitted fabrics to which 15 it is desired to impart an ornamental appearance; and it consists in a series of parallel stripes arranged diagonally of the fabric with respect to the successive rows or courses of loops composing the same, with short parallel 20 stripes interposed between them and lying at substantially right angles thereto.

In the photographic illustration the main or diagonal stripes are shown at A A, &c., and the short parallel stripes at B B, &c. The 25 stripes A A, &c., are of the denticulated form, with both edges thereof indented, as shown, and are disposed in parallel relation and diagonally of the fabric with respect to the successive rows or courses of loops composing

the same. Between these stripes A A, &c., 30 are arranged the short stripes B B, &c., which are disposed in parallel relation with respect to one another and at substantially right angles to the former, the arrangement being such that a series of continuous parallel denticulated stripes is shown inclined diagonally of the fabric in one direction and the short parallel stripes inclined in the other. 35

Having thus described my invention, what I claim as new, and desire to secure by Letters 40 Patent of the United States, is—

The design for surface ornamentation of 45 knitted fabrics, consisting of a series of denticulated stripes arranged in parallel relation and disposed diagonally of the fabric with respect to the successive rows or courses of loops composing the same, with short parallel stripes interposed between them and lying at right angles thereto, substantially as shown and described. 50

In testimony whereof I have hereunto set my hand this 27th day of February, 1888.

JEREMIAH P. HARRIMAN.
